Term of patent 14 years

(Cl. D78—1)

FIG. 2

FIG. 1

FIG. 3

FIG. 1 is a perspective view of a butterfly valve body embodying my novel design.

FIGURE 2 is a side elevational view of the same.

FIG. 3 is a top plan view of the same.

The side opposite that shown in FIGS. 1 and 2 is a mirror image thereof.

The bottom not shown is substantially the same as the top.

I claim:

The ornamental design for a butterfly valve body, as shown and described.
